UNITED STATES PATENT OFFICE.

MAURICE ALEX. COOK, OF PEORIA, ILLINOIS, ASSIGNOR TO THE COOK HEATER COMPANY, OF PEORIA, ILLINOIS.

SECTIONAL BOILER.

No. 821,705.

Specification of Letters Patent.

Patented May 29, 1906.

Application filed May 10, 1905. Serial No. 259,696.

To all whom it may concern:

Be it known that I, MAURICE ALEX. COOK, a citizen of the United States, and a resident of Peoria, in the county of Peoria and State of Illinois, have invented a new and Improved 5 Sectional Boiler and Generator, of which the following is a full, clear, and exact description.

This invention relates to boilers or generators; and it consists, substantially, in the construction and combinations of parts herein-after particularly described, and pointed out in the claims.

The invention has reference more especially to boilers or generators for hot water and steam to be used for heating and other purposes; and one of the principal objects thereof is to overcome numerous disadvantages and objections common to many other 20 structures hitherto devised with like ends in view.

Another object is to provide a structure of the kind referred to which is sectional in character and readily taken apart and again put together and which is not incapacitated for use or operation in the event of any one or more of the sections thereof becoming cracked or broken.

A further object is to provide a structure 30 of this kind which for given dimensions possesses a maximum water-containing capacity, besides presenting a maximum area of surface to the heat and products of combustion from the fire-chamber and which is also 35 capable of ready access and easy repair and control.

A still further object is to provide a structure of the class mentioned which is economical in its consumption of fuel, as well as in 40 other respects, and which is also strong and comparatively inexpensive in its embodiment, besides being well adapted for long and repeated service.

The above and additional objects are attained by means substantially such as are illustrated in the accompanying drawings, in which similar characters of reference indicate corresponding parts in all the figures.

Figure 1 is a view in side elevation of a furnace provided with a boiler constructed in accord with this invention, parts of the furnace and boiler structure being broken away to show the internal construction thereof.

Fig. 2 is a vertical section upon the line 2 2 of Fig. 1. Fig. 3 is a front elevation of the furnace with parts broken away to show the internal construction. Fig. 4 is a perspective view of two oppositely-arranged coöperating boiler-sections. Fig. 5 is a vertical section as the same would appear on the line X X of 60 Fig. 1. Fig. 6 is a vertical section as the same would appear on the line Y Y of Fig. 1. Fig. 7 is a view in front elevation of a furnace with the front removed and with a boiler-dome of different type from that shown in 65 the preceding views, and Fig. 8 is a perspective view of a dome of the kind shown in Fig. 5.

Before proceeding with a more detailed description it may be stated that in the form of 70 my improvements herein shown I employ a suitable furnace or casing in which are mounted, preferably, duplicate series of specially-constructed water-containing sections which are so organized as to form a fire-chamber 75 and an ash-pit extending practically from front to rear of the structure, the sections of each series having suitable water connection with each other and those of the two series being in communication with a steam-dome 80 common to all the sections, the said furnace or casing being provided with doors for access to both the fire-chamber and ash-pit, as well as to suitable dampers or valves located in conduits or flues formed by the sections. 85

A suitable escape-flue is provided for the smoke and other products of combustion and suitable air-supplies are also provided, and while I have herein represented my improvements in a certain selected embodiment it 90 will be understood, of course, that I am not limited to the precise details thereof in practice, since immaterial changes therein may be resorted to coming within the scope of my invention. 95

Specific reference being had to the drawings by the designating characters marked thereon, and more particularly to Figs. 1 to 4, 1, Fig. 3, represents a suitable furnace or casing, interiorly of which are mounted duplicate series of boiler-sections 2 embodying my improvements, said sections being organized into duplicate oppositely-disposed series for effective operation. As shown in Figs. 1, 2, and 4, each of said sections 2 is hollow through 100 out and is formed for its full height with a 105

vertical side portion 3, thickest at the bottom, while projecting inwardly and downwardly from which at the upper end thereof is a head 3^a, having an inner hanging member 4, provided at the intersection thereof with the head, being an inward extension 5, the face 6 of which is preferably in a vertical plane, as shown. At the lower end of each of the said hanging members 4 is a branch 49, connecting with the side portion 3 of the section and provided with a number of pendant pockets 7, the same being preferably (though not essentially) tapered downwardly and of suitable depth, while above said pockets the section is constructed therethrough from front to rear with preferably rectangular openings 8 and 9, from the top or upper part of one or both of which may depend similar pockets 10, it being noted that each of the said pockets 7 and 10 may be provided with a central partition 11 (dotted lines, Fig. 2) to assist in the circulation of water through the section. The said top or upper part of opening 8 is formed by a branch 4^b, corresponding to 4^a, connecting with the inner hanging member 4 the side portion 3, while the top or upper part of opening 9 is formed by the head 3^a, as will be understood from Fig. 4. When the sections of each series are properly organized, as in Fig. 1, the sides of said openings 8 and 9 form conduits or flues for the passage from end to end of the structure of the products of combustion, as will hereinafter be explained. Beginning at a point substantially in line with the top or upper part of each of the openings 9 the inner hanging members 4 are somewhat reduced in dimensions longitudinally of the furnace at 12, so as to form between the adjacent or opposite faces of said members of each series of sections 2 the vertical passages 13, Fig. 1, which are in communication with the conduits formed by the openings 8 and 9, as well as with a central vertical chamber 14, formed between the inner sides of the members, the upper part of said chamber being closed by the bringing together of the vertical faces 6 of the hereinbefore-mentioned inward extensions 5 of the sections 2 of the two series thereof. The sections of each series are preferably provided on the upper surfaces of the heads 3^a thereof with suitable lugs 15, having alined openings therein, through which a rod 16, Figs. 2 and 3, may be inserted, if desired, for securing the sections together, and said sections are also provided on their outer lower sides with similarly-constructed lugs 16^a, through which another rod 17 (dotted lines, Fig. 1, and full lines, Fig. 2) may be passed for the same purpose. Connecting the tops of the heads 3^a of the sections of the two series is a steam-dome 18, the same communicating with said heads by means of vertical supporting-nipples 19 therefor. Also at the outer lower sides thereof the sections are connected with each other

by means of headers 21, as shown, and it will be understood that in the event of any one or more of the sections becoming cracked or broken in use the same may be readily removed or disconnected from the remaining sections without in any manner interfering with the operation of the structure. Beneath the said pockets 7 the vertical side portions 3 of the sections form the sides of a fire-chamber 22, in which is supported, by means of inward notched extensions 23 of said side portions, a suitable grate 24, connected by suitable connecting means with a shaking-lever 25. The said fire-chamber is in direct communication with the said chamber 14, and beneath the fire-chamber is the ash-pit 28, while supported in any suitable manner against the front faces of the foremost sections of the two series of sections is a water-front 29, which is preferably in communication with the said sections. 75 80 85

Located a suitable distance beyond the rear faces of the rearward sections of the two series is a frame 30, extending the full height and width of the structure, and the same is provided with the upper and lower rectangular openings 30^a and 30^b, (see Figs. 1 and 6,) and disposed in front of the upper half of said lower rectangular opening 30^b thereof is a water-back 31, having forwardly-projecting pockets 32, said water-back extending upwardly from a line just above the grate-bars to a point somewhat below the plane of the lower ends of the pockets 7, before referred to. 90 95

The rear end of the chamber 14 between the inner sides of the members is closed by a plate 48, placed in juxtaposition to the rear faces of the rearward sections, substantially as seen in Figs. 1 and 5, and so retained by securing a transverse extension 49 of the said plate to the inner face of the frame 30, just below the lower edge of the upper opening 30^a in the said frame, which serves as a partition on the upper wall of a chamber 50, the lower wall of which is an inturned portion of the frame 30, as shown in Fig. 1. This chamber 50 provides connection between the fire-chamber and the conduits or flues 8 to permit the products of combustion to pass from the fire-chamber up and over the water-back 31, into the chamber 50, and thence into the conduits or flues 8. 100 105 110 115

Attached to and projecting rearwardly from the frame 30 and communicating with the conduits or flues 9 in the sections through the provision of the upper opening 30^a in the frame 30 is a casing 34, serving as an exit-pipe for the products of combustion, which pass forwardly through the conduits or flues 8 and then rearwardly through the conduits or flues 9 and out through the opening 30^a in the frame 30 and the exit-pipe, as aforesaid. (See Figs. 1 and 6.) 120 125

Beyond the frame 30 and spaced therefrom a suitable distance is a rear end wall 35, 130

the same having a suitable opening through which the exit-pipe 34 projects, as shown in Fig. 1, and between the end wall 35 and the frame 30 is provided an air-chamber 36. Air 5 may be admitted into the chamber through an inlet 37 in the end wall 35, which is closed by a valve 38. The width of the inlet-opening and valve for closing the same is approximately the same width as the casing serving 10 as the exit-pipe, a cross-section of which is seen in Fig. 6, and air entering the inlet 37 will pass down and around the opposite sides of the exit-pipe and take the direction indicated by the arrows in Fig. 1. It will be seen 15 that the front of the furnace is provided, preferably, with a plate 39, having double doors 40 for access to the draft-passages. A single door 41 for the ash-pit and a door 42 for access to the fire-chamber are provided 20 in the water-front. On the inner side thereof beneath the pockets 7 each section is provided with a downwardly-extending baffle-plate 43, and each section is provided on opposite sides with grooves 43^a, Figs. 2 and 5, 25 of semicircular cross-section, which coöperate to form air-inlets 44, Fig. 1, beneath the baffle-plates, thus enabling additional quantities of air to be admitted to the fire-chamber for producing a more intimate admixture of the 30 smoke and gases arising therein, with a minimum deposit of soot upon surrounding parts. I sometimes provide the opposite sections of the two series with perforated ribs 45 for securing said sections together, (see Fig. 4,) 35 and, as also shown in said figure, it will be seen that instead of employing duplicate series of sections I may employ a single one only of each series, according to the capacity of structure desired.

40 The bottoms of the conduits formed by the alining openings 8 and 9 of the sections may be provided with suitable dampers 46, (shown in Figs. 1 and 2, although broken away in Fig. 1,) which are provided with a series of 45 openings 47 therein. The upper and lower dampers are preferably connected by the straps or bars 51, as shown in Fig. 1, which pass out through the front of the furnace and have attached thereto the rings 52, by means 50 of which an operator may adjust the said dampers. When the dampers are in the position shown in Fig. 1, a return draft is produced—that is, the products of combustion pass into the rear ends of the conduits or flues 8 and from the same into the front ends 55 of the conduits or flues 9 and out through the exit-pipe 34, as specified; but on sliding the dampers outwardly the openings 47 in the dampers are caused to coincide and communicate with the vertical passages 13, giving a straight draft from the fire-chamber to the exit-pipe through the conduits or flues 9, which is an advantage when first starting the furnace or when it is desired to quickly heat 60 the same.

The structure may be supplied with water at any suitable point thereot and may also be provided with any suitable outlet from which hot water may be taken to any point for consumption or use.

70 From the foregoing it will be seen that air will enter the air-chamber 36 through the valved inlet thereof and will pass downwardly upon opposite sides of the casing 34, forming the exit-pipe, as indicated by the 75 arrows marked *a* in Fig. 1, and thence upwardly through the grate and fuel thereon into the fire-chamber above the fuel, where it mixes with the gases and other products of combustion which pass upwardly and over 80 the water-back 31, as indicated by the arrows marked *b* in Fig. 1, into the chamber 50, thence forwardly through the conduits or flues 8 and rearwardly through the conduits or flues 9, the flames and heat in the 85 meantime impinging upon the surface portions presented by the inner parts of the structure and the products of combustion finally passing out through the opening 30^a 90 in the frame 30 and the exit 34, as is apparent. The structure is most effective and reliable in use, and it is thought the advantage and operation thereof will be fully understood without further elucidation.

95 On referring to Fig. 2 it will be seen that the lower portion of each boiler-section, beginning from the baffle-plate 43 and running downwardly, is tapered, making the section considerably larger at the base than at the point on a line with the baffle-plate. This 100 feature not only reduces the grate-space to the proper proportion, but also accommodates an increased volume of water at a point where the return-headers 21 are connected, thereby preventing fluctuations of water in 105 the boiler and making it possible to keep a steady water-line in the boiler when using it for steam instead of water.

110 On referring to Fig. 3 it will be seen that the front of the furnace or casing is made of two parts, the upper portion preferably of solid cast-iron with the draft-doors and openings as shown, while the lower portion is hollow and is connected with the sections so as to allow a free circulation of water through 115 the hollow portion. This lower portion, forming, as it does, the front of the fire-box and coming in contact with the combustion, adds materially to the heating-surface of the boiler.

120 In Fig. 7 I have illustrated a boiler in which the boiler-sections are substantially the same in structure as those already described, differing therefrom only in having the ribs 45 removed. In this form of boiler 125 the sections at the sides of the boiler are not brought together at the top, as in the form of boiler already described, but the said sections are spaced apart to permit the insertion therebetween of a boiler-dome 18^a of consid- 130

erably larger size than the dome 18 used in the form of boiler already described and having a pendent portion 18^b, which extends downward into a chamber 14^a of considerably larger size than the chamber 14 formed between the side sections of the boiler when they are properly disposed together. The dome 18^a is connected with the side sections of the boiler in precisely the same way as the dome 18 which it replaces, and the circulation of water and steam throughout the sections of the boiler is brought about in precisely the same manner. In this form of boiler, however, it is necessary to employ a water-back 22^a of considerably greater width than the ordinary back 31, and the grate 24^a employed is wider, of course, than the ordinary grate 24; otherwise the boiler structures are substantially identical. In constructing a furnace with a boiler provided with a dome of the form 18^a it is necessary to provide special end plates, and the doors are wider or else set farther apart than in the form already described; but as such changes in the furnace structure are obvious a specific illustration thereof is regarded as unnecessary.

Having thus described my invention, I claim as new and desire to secure by Letters

30 Patent—

1. A sectional boiler, comprising duplicate, hollow, separable sections arched at the upper portions thereof to form an intermediate chamber, the lower portions of the sections forming a fire-chamber and an ash-pit, an air-chamber communicating with the ash-pit, and having a valved inlet, an exit for the products of combustion, a dome centrally of said sections above the same, and communicating vertical nipples supporting the dome upon the sections.

2. A sectional boiler comprising duplicate hollow sections provided at their upper portions with heads, having hanging members, said sections being formed with openings extending from front to rear thereof, the bottom parts of said members having branches connecting with the sections and formed with depending pockets.

3. A sectional boiler comprising duplicate hollow sections provided at their upper portions with abutting heads, having hanging members, said sections being formed with openings extending from front to rear thereof, the tops of said openings being in connection with the sections and formed with depending pockets.

4. A sectional boiler comprising duplicate hollow sections provided at their upper portions with coöperating heads, having hanging members, said sections being formed with openings extending from front to rear thereof, the parts forming the bottom and top of each of said openings being formed with depending pockets.

5. A sectional boiler, comprising duplicate series of hollow sections coöperating at the upper portions thereof to form an intermediate chamber, the lower portions of said duplicate series forming a fire-chamber and an ash-pit, headers connecting the sections of each series, a steam-dome connecting the sections of the two series, an air-supply, an exit for the products of combustion, and a water-back having forwardly-projecting pockets. 75

6. A sectional boiler, comprising duplicate series of hollow sections coöperating at the upper portions thereof to form an intermediate chamber, the lower portions of said duplicate series forming a fire-chamber and an ash-pit, headers connecting the sections of each series, a steam-dome connecting the sections of the two series, an air-supply, an exit for the products of combustion and a water-back having forwardly-projecting pockets, 80 said steam-dome extending within said intermediate chamber between the sections. 85

7. A sectional boiler, comprising duplicate series of hollow sections coöperating at the upper portions thereof to form an intermediate chamber, the lower portions of said duplicate series forming a fire-chamber and an ash-pit, headers connecting the sections of each series, a steam-dome connecting the sections of the two series, an air-supply, an exit 90 for the products of combustion and a water-back having forwardly-projecting pockets, 95 said steam-dome extending within said intermediate chamber between the sections, and the adjacent sides of the sections of each series being constructed with recesses to form air-inlet passages, substantially as shown and described. 100

8. A sectional boiler, comprising duplicate series of hollow sections coöperating at the upper portions thereof to form an intermediate chamber, the lower portions of said duplicate series forming a fire-chamber and an ash-pit, headers connecting the sections of each series, a steam-dome connecting the sections of the two series, an air-supply, an exit 105 for the products of combustion and a water-back having forwardly-projecting pockets, 110 said steam-dome extending within said intermediate chamber between the sections, and the adjacent sides of the sections of each series being constructed with recesses to form air-inlet passages, substantially as shown and described, the inner surfaces of the sections having baffle-plates located above the inner 115 ends of said passages. 120

9. A sectional boiler comprising duplicate hollow sections provided at their upper portions with abutting heads, having hanging members and being formed with openings extending from front to rear thereof, the upper portion of adjacent sections being spaced apart for a portion of their length to provide vertical passages therebetween which are adapted to be in communication with the 130

openings in the said sections, and the tops of said openings being in connection with the sections and formed with depending pockets.

10. A sectional boiler comprising hollow sections provided at their upper portions with coöperating heads, having hanging members and being formed with openings extending from front to rear thereof, the upper portion of adjacent sections being spaced 10 apart for a portion of their length to provide vertical passages therebetween which are adapted to be in communication with the openings in the said sections, the parts forming the bottom and top of each of said openings being formed with depending pockets.

11. A sectional boiler comprising duplicate hollow sections provided at their upper portions with heads, having hanging members, said sections being formed with openings 20 extending from front to rear thereof, the bottom parts of said members having branches connecting with the sections and formed with depending pockets, and said pockets being provided with a central partition, substantially 25 as shown.

12. A sectional boiler comprising duplicate hollow sections provided at their upper portions with abutting heads, having hanging members, said sections being formed with 30 openings extending from front to rear thereof, the tops of said openings being in connection with the sections and formed with depending pockets, and said pockets being provided with a central partition, substantially 35 as shown.

13. A sectional boiler comprising duplicate hollow sections provided at their upper portions with coöperating heads, having hanging members, said sections being formed with 40 openings extending from front to rear thereof, the parts forming the bottom and top of each of said openings being formed with depending pockets, and said pockets being provided with central vertical partitions substantially 45 as shown.

14. A sectional boiler comprising duplicate hollow sections provided at their upper portions with heads, having hanging members and being formed with openings extending 50 from front to rear thereof, the upper portions of adjacent sections being spaced apart for a portion of their length to provide vertical passages therebetween which are adapted to be in communication with the openings in 55 the said sections, the bottom parts of said members having branches connecting with the sections and formed with depending pockets.

15. A sectional boiler, comprising duplicate, hollow, separable sections, arched at the upper portions thereof, to form an intermediate chamber, the lower portions of the sections forming a fire-chamber and an ash-pit, the adjacent sections formed with upper 65 and lower intercommunicating openings to

provide return-flues longitudinally disposed through the said sections, a closure for the rear end of the chamber formed intermediate the upper portions of said sections, an air-supply at the rear of the said boiler, an exit 70 for the products of combustion in communication with the upper intercommunicating openings through the said sections and a dome centrally of said sections above the same, and communicating vertical nipples 75 supporting the dome upon the sections.

16. A sectional boiler, comprising duplicate, hollow, separable sections, arched at the upper portions thereof to form an intermediate chamber, the lower portions of the 80 sections forming a fire-chamber and an ash-pit, the adjacent sections formed with upper and lower intercommunicating openings to provide return-flues longitudinally disposed through the said sections and the upper portion of adjacent sections being spaced apart for a portion of their length to provide vertical passages therebetween which are adapted to be in communication with the openings through the said sections, a closure for the 85 rear end of the chamber formed intermediate the upper portions of said sections, an air-supply at the rear of said boiler, an exit for the products of combustion in communication with the upper intercommunicating 90 openings through the said sections, and a dome central of said sections above the same, and communicating vertical nipples supporting the dome upon the sections.

17. A sectional boiler comprising duplicate, hollow, separable sections arched at the upper portions thereof to form an intermediate chamber, the lower portions of the sections forming a fire-chamber and an ash-pit, the adjacent sections formed with upper and 100 lower intercommunicating openings to provide return - flues longitudinally disposed through the said sections and the upper portion of adjacent sections being spaced apart for a portion of their length to provide vertical 105 passages therebetween which are adapted to be in communication with the openings through the said sections, a closure for the rear end of the chamber formed intermediate the upper portions of said sections, dampers 110 for shutting off the communication between the passages intermediate the said sections and the openings therethrough, means for operating the said dampers, an air-supply at the rear of said boiler, an exit for the products of 115 combustion in communication with the upper intercommunicating openings through the said sections, and a dome central of said sections above the same, and communicating vertical nipples supporting the dome upon 120 the sections.

18. A sectional boiler, comprising duplicate series of hollow sections coöperating at the upper portions thereof to form an intermediate chamber, the lower portions of said 125

- duplicate series forming a fire-chamber and an ash-pit, a frame spaced beyond the rear faces of the rearward sections of the duplicate series and provided with upper and lower openings therethrough, the adjacent sections formed with upper and lower intercommunicating openings to provide return-flues longitudinally disposed through the said sections, a plate supported by the said frame and forming a closure for the rear end of the chamber formed intermediate the upper portions of said sections, an air-supply at the rear of the said frame adapted to have communication with the ash-pit through the lower opening in the said frame, and an exit for the products of combustion in communication through the upper opening in the frame with the upper intercommunicating openings through the said sections.
19. A sectional boiler, comprising duplicate series of hollow sections coöperating at the upper portions thereof to form an intermediate chamber, the lower portions of said duplicate series forming a fire-chamber and an ash-pit, a frame spaced beyond the rear faces of the rearward sections of the duplicate series and provided with upper and lower openings therethrough, the adjacent sections formed with upper and lower intercommunicating openings to provide return-flues through the said sections, a plate supported by the said frame and forming a closure for the rear end of the chamber formed intermediate the upper portions of said sections, a steam-dome connecting the sections of the two series, a water-back disposed in front of the lower opening of the said frame and having forwardly-projecting pockets, an air-supply, and an exit for the products of combustion, the same being in communication with the upper intercommunicating openings through the said sections.
20. A sectional boiler comprising duplicate series of hollow sections coöperating at the upper portion thereof to form an intermediate chamber, a closure for the rear end of the said chamber, the lower portions of said duplicate series forming a fire-chamber and an ash-pit, and the adjacent sides of the lower portions of the sections of each series being constructed with recesses to form air-inlet passages, inwardly and downwardly project-
- ing baffle-plates attached to the inner faces of said sections in front of the inner ends of said passages, an air-supply controlled by a valve-inlet at the rear of the said boiler, and an exit for the products of combustion.
21. A sectional boiler, comprising duplicate series of hollow sections having intercommunicating openings to provide return-flues through the said sections, and coöperating at the upper portions thereof, to form an intermediate chamber, a closure for the rear end of the said chamber, the lower portions of said duplicate series forming a fire-chamber and an ash-pit, and the adjacent sides of the sections of each series being constructed with recesses to form air-inlet passages, and baffle-plates formed on each section and located in the front of the inner ends of said air-inlet passages, an air-supply controlled by a valve-inlet at the rear of the said boiler, and an exit for the products of combustion, the same communicating with the upper openings through the said sections.
22. A sectional boiler, comprising duplicate series of hollow sections having intercommunicating openings to provide return-flues through the said sections, and coöperating at the upper portions thereof, to form an intermediate chamber, a closure for the rear end of the said chamber, the lower portions of said duplicate series forming a fire-chamber and an ash-pit, and the adjacent sides of the sections of each series being constructed with recesses to form air-inlet passages, and baffle-plates formed on each section and located in the front of the inner ends of said air-inlet passages, a steam-dome connecting the sections of the two series, an air-supply controlled by a valve-inlet at the rear of the said boiler, an exit for the products of combustion, the same communicating with the upper openings through the said sections, and a water-back located at or near the rear end of the boiler and having forwardly-projecting pockets.
